Fig.7

The rear and bottom, not shown, are substantially flat and plain. The ends, not shown, are substantially the same as the ends shown.

The broken line showings of the lamp bulbs are for illustrative purposes only.

This is a continuation-in-part of my co-pending application Serial No. D. 79,228, filed March 27, 1964, now abandoned.

I claim:

The ornamental design for a music rack lamp, as shown and described.
